DUST SAMPLER

Hermannus van Tongeren, Heemstede,
NetherlandsApplication November 26, 1940, Serial No. 367,294
In Germany December 21, 1939

4 Claims. (Cl. 73—21)

The determination of the dust concentration of gases flowing, for instance, through a chimney is usually effected by means of a sampler or dustometer, through which the gas is drawn and by which the whole cross-section of the chimney is "scanned." Provision should be made that the gas velocity at the inlet of the sampler be always equal to that of the surrounding gases, in order to avoid objectionable separation of the dust fractions. Known samplers communicate with apparatus, which completely separates the dust still contained in the gas discharged by the sampler. In series with said apparatus there are provided a cooler with a water trap, a device for measuring the quantity of gas passed through the sampler, and a pump for drawing the gas through the plant, said pump being provided with suitable controlling devices. A plant as above described is rather complicated and requires very skilled operators.

My invention has for its object to provide a sampler, by means of which the required tests can be carried out in a much simpler and, consequently, cheaper way.

First of all, I dispense with the complete separation of the dust from the gas shunted through the sampler. This is very important, since complete separation involves the use of a paper filter or the like, i. e. a filter offering much resistance to the flow of the gas, thus necessitating the use of a powerful pump. As a matter of course, partial collection of the dust from the shunt, as contemplated by the invention, requires certain corrections, which will be considered later.

Further, according to this invention, the dust laden main flow to be analyzed is itself utilized as a source of energy for drawing the shunt through the sampler, so that the velocity of the shunt may always have the same value as that of the main stream. In this manner I obviate the troublesome adjustment of the velocity of the shunt during the "scanning" of the cross-section of the chimney, which is indispensable when using the said known plant.

In order that my invention may be more fully understood, I shall now describe the same with reference to the annexed drawing, in which:

Fig. 1 is a vertical cross-section and

Fig. 2 is a top elevation of a sampler constructed in accordance with my invention, whereas

Fig. 3 shows how said sampler is suspended in a chimney.

Referring to Fig. 3 of the drawing, the sampler A is suspended within a chimney B by means of

strings from a bar C projecting from the chimney through an aperture D, so that the operator is capable of "scanning," with the sampler, the whole cross-section of the chimney. The inlet for the shunt is indicated by E.

The sampler represented in Figs. 1 and 2 comprises a vertical cyclone 4 of normal design, which is provided with a horizontal and tangential gas inlet conduit 5. This conduit communicates with 10 a vertical, downwardly directed pipe 6 provided with a bottom inlet nozzle 7, through which the shunt is drawn in. At the junction between pipe 6 and conduit 5, curved, parallel vanes 8 are provided with a view to reducing the resistance to flow. At its top side the cyclone 4 has a cleaned gas outlet conduit 9.

The dust thrown out in the cyclone is discharged, through the inverted cone 10 of the cyclone, to a cylindrical dust receptacle 11 having 20 a hemispherical bottom. Said receptacle has an air-tight connection with a cylindrical jacket 13 surrounding the cyclone 4 and serving to prevent undesirably eddy currents from setting up in the main stream. The bottom of receptacle 11 is located at a considerably higher level than the inlet nozzle 7.

The outlet pipe 9 of the cyclone 4 has a flaring mouth 9a opening into the throat of a Venturi tube 12. The jacket 13 has a tapering top portion 13a, the top edge of which is connected to that of the flaring mouth 9a of the cyclone outlet pipe 9. The Venturi tube 12 is surrounded by a jacket 14 serving the same purpose as jacket 13.

If the described device is suspended, as illustrated in Figure 3, in a chimney, part of the combustion gas is shunted through the inlet nozzle 7 so as to flow through pipe 6 and conduit 5 into the cyclone 4, in which by far the greater portion of the dust particles is thrown out and discharged into the receptacle 11. The cleaned gas, which still contains a certain amount of fines or flour, returns into the chimney through the outlet pipe 9, 9a and the Venturi tube 12.

Owing to the fact that the bottom of receptacle 11 lies at a considerable distance above the inlet nozzle 7, the latter is not affected by eddy currents set up by said bottom, so that in nozzle 7 no separation of dust fractions can take place and the dust concentration of the shunt flowing through the sampler accurately corresponds with that of the surrounding gases.

Venturi tube 12 serves to overcome the resistances offered to the flow of the shunt on its way from the inlet nozzle 7 to the mouth of the outlet pipe 9, 9a. In the passage surrounding the

tapering top portion 13a, the velocity of the main stream is increased owing to the fact that both the width and the radius of the annular cross-section of said passage decreases in upward direction, so that suction is created at the mouth 9a. The dimensions of the sampler should be so chosen that this suction just suffices to overcome the aforesaid resistances. This can be checked in the wind tunnel. Slight deviations can be compensated by means of the correction nozzle 7, which, according to Fig. 1, has a slightly smaller cross-section than pipe 6. As long as the cross-sectional area of nozzle 7 is not essentially different from that of pipe 6, this manner of compensating is scientifically justifiable.

It is, however, to be understood that nozzle 7 should only be used to effect the very last correction. The principal means for equalizing the velocities of the shunt and of the main flow is the Venturi tube 12, in which the energy of the main stream itself is utilized for drawing the shunt through the sampler. This feature and the automatic equalization of the said velocities are salient features of my present invention.

Another important feature is the air-tight sealing of the dust receptacle 11 and the fact that the latter communicates merely with the cyclone, through the dust outlet thereof. Thus, the operation of the cyclone cannot be impaired by the varying dust level in the receptacle.

As already stated, the cyclone does not effect a complete separation of the dust suspended in the shunt. As a consequence, the dust concentration of the main stream cannot simply be calculated from the collection in receptacle 11 and the amount of gas passed through the meter in a given time interval, nor does the grading of the collection correspond with that of the dust in the main stream. However, the desired values can readily be determined if it is known how the efficiency of the cyclone depends on the velocity of the shunt at the inlet 7 and on the size of the dust particles carried therewith. This dependency can be predetermined in the laboratory. For various gas velocities and for various specific weights of the dust, the efficiency of the cyclone is plotted against the size of the grains in various fractions between 0 and say 500 μ . With the aid of the resultant curves and of the easily determinable average inlet velocity, one can readily calculate, from the amount and the grading of the sample collected in receptacle 11, the actual concentration and grading of the dust contained in the flue gases sucked through the sampler.

Although the invention has more especially been described in connection with flue gases passing through a vertical conduit, it can of course also be used for analysing other dust laden gases, or gases flowing in horizontal or inclined conduits.

What I claim is:

1. A dust sampler unit adapted to be manually positioned over a selected zone of the cross sectional area of a chimney through which dust laden gas is flowing, comprising; a cyclone having a tangential dust laden gas inlet, a cleaned gas outlet and a dust discharge opening; a closed dust receptacle arranged substantially coaxially with the cyclone and communicating with the dust discharge opening thereof, a shunt pipe communicating at its upper end with said gas inlet of the cyclone and having its body disposed in parallel relation with the axis of the cyclone, said shunt pipe having its lower inlet end dis-

posed below the bottom of the dust receptacle to receive dust laden gas before turbulence therein is caused by the presence of the unit, nozzle means at the lower end of the shunt pipe for

5 maintaining gas velocity in the shunt equal to the gas velocity of the gas stream enveloping the unit, a Venturi tube disposed substantially coaxially with the cyclone, the cleaned gas outlet of the cyclone opening into the Venturi tube substantially in the throat thereof, and means for portably supporting said dust sampler.

2. A dust sampler unit adapted to be manually positioned over a selected zone of the cross sectional area of a chimney through which dust

15 laden gas is flowing, comprising; a cylindrical jacket having an inwardly tapering top portion; a cyclone within the jacket having a horizontal tangential dust laden gas inlet, a cleaned gas outlet conduit having an outwardly flaring mouth joining with the upper edge of the inwardly tapering top portion of the jacket, and a dust discharge cone; a dust laden gas shunt pipe having its longitudinal axis parallel with the axis of the cyclone and communicating at its upper 20 end with the said tangential gas laden dust inlet, an inlet nozzle on the bottom end of the shunt pipe for maintaining the gas velocity in the shunt equal to the velocity of the gas stream enveloping the sampler, a dust collecting receptacle having an air-tight connection with the lower end of the jacket and adapted to receive dust from said cone, the bottom of said receptacle being located above the nozzle of the shunt pipe whereby the inlet of the shunt is below the zone

25 of turbulence caused by the presence of the sampler in the gas stream, a Venturi tube having its inlet throat telescopically fitting over the end of the cleaned gas outlet conduit and in spaced relation to the inwardly tapering top portion of the jacket, thereby to create suction at the mouth of said outlet conduit to overcome resistance to gas flow in the shunt on its way from the nozzle to the mouth of the outlet conduit, and means for supporting the sampler in a selected position 30 in the chimney.

3. A dust sampler unit according to claim 2 wherein the junction between the tangential inlet for the cyclone and the top portion of the shunt pipe is provided with a plurality of spaced parallel substantially right-angularly curved vanes for reducing the resistance to gas flow from the shunt pipe to the cyclone.

4. In a dust sampler comprising a cyclone having a tangential dust laden gas inlet and a clean gas outlet and a dust discharge opening, a closed

55 dust receptacle arranged substantially coaxially with the cyclone and communicating with the dust discharge opening thereof, a gas inlet pipe arranged with its long axis parallel to the axis of the cyclone and having one end in communication with said dust laden gas inlet and its other end provided with an inlet opening directly into the surrounding atmosphere below the dust receptacle, and a Venturi tube having its axis in substantially parallel relation with the axis of said gas inlet pipe and having an inlet opening, an outlet opening and a throat, the cleaned gas outlet of the cyclone opening into the Venturi tube substantially in the throat thereof, and the said inlet opening of the Venturi tube being located downstream of the inlet end of the gas inlet pipe.
